Inventor:
Thomas G. Booth.

By Charles S. Gooding, M.M.

UNITED STATES PATENT OFFICE.

THOMAS G. BOOTH, OF BOSTON, MASSACHUSETTS.

MACHINE FOR SEPARATING FIBERS FROM FIBER-YIELDING PLANTS.

Application filed December 5, 1927. Serial No. 237,664.

This invention relates to improvements in a machine for treating the stalks of fiber yielding plants, such as, flax, hemp, sisal, ramie, and the like, thereby separating said fibers, which are valuable in the textile and cordage industries, from the woody boon which comprises a greater portion of the stalks and which is of relatively small value as compared to that of the fibers, but which 10 may be utilized nevertheless to great advantage in the paper-making industry.

The object of the invention is to provide a machine for separating the fibers from the boon in an effective manner without breaking or injuring the fibers, and this result is 15 accomplished by employing a plurality of tapered fluted rolls grouped in pairs, the rolls of each pair tapering in the same direction with respect to each other, and alternate pairs of rolls tapering in opposite directions respectively.

Applicant is aware that both plain and fluted rolls have been employed heretofore for breaking and opening the stalks of fiber 20 bearing plants, but other means have also been utilized in conjunction with these rolls to aid in opening the fibers, with the result that the fibers have been so harshly treated that they are either injured and 25 broken and their value greatly reduced. In the device of this invention the tapered rolls impart a biasing action to the stalks as they 30 pass from one pair of rolls to another, with the result that the stalks are broken and 35 opened and the boon separated from the fibers in a much more effective manner than formerly and without injuring the fibers.

The invention consists in a machine for 40 separating the fibers from the stalks of fiber yielding plants as set forth in the following specification and particularly as pointed out in the claims thereof.

Referring to the drawings:

Figure 1 represents a side elevation of a 45 machine embodying my invention.

Fig. 2 is a side elevation of the opposite side of the machine from that illustrated in Fig. 1.

Figs. 3, 4, 5, 6 and 7 are vertical sectional 50 views through co-operating pairs of rolls which are utilized in treating the stalks.

Fig. 8 is a sectional view through a device for combing the fibers as the latter pass therethrough.

Fig. 9 is a vertical section through another pair of rolls. 55

Fig. 10 is an enlarged sectional elevation taken on the line 10—10 of Fig. 1, looking in the direction of the arrows on said line.

Fig. 11 is an enlarged sectional elevation 60 taken on the line 11—11 of Fig. 1, looking in the direction of the arrows on said line.

Fig. 12 is a diagrammatic plan view illustrating the biasing action imparted to the stalks as the latter pass between the tapered 65 rolls.

Like numerals refer to like parts throughout the several views of the drawings.

In the drawings, 1 represents a frame and 70 2 is a main driving shaft which extends transversely across the frame and is mounted in suitable bearings thereon. Rigidly fastened to the driving shaft 2 at one end thereof is a driving pulley 3, and rigidly fastened to said shaft at the opposite end 75 thereof is a gear 4, the latter meshing with a pinion 5 rigidly fastened to a countershaft 6 which extends longitudinally of the frame 1 upon one side thereof. The countershaft 6 is mounted in a plurality of bearings 7 80 fastened to the frame. Also rigidly fastened to the countershaft 6 are pinions 8, 9 and 10 which mesh with gears 11, 12 and 13 in turn rigidly fastened to auxiliary driving shafts 14, 15 and 16 respectively, said shafts 85 extending transversely of the frame 1 and being mounted in suitable bearings upon said frame.

The rolls which are employed in treating the stalks are arranged in groups A, B, C, 90 D, E and F at the top of the machine, each group comprising one or more pair of co-operating rolls of the same type.

The stalks are first conducted to the group A, which consists of a plurality of cylindrical rolls 17, see Fig. 3, mounted upon shafts 18 in turn mounted in bearings 19. Gears 20 are rigidly fastened to each of the shafts 18 and each pair of said rolls are geared together in a manner to cause the material to 100 be fed therethrough. The rolls 17 are utilized to crush and break the woody boon of the stalks.

From the group A of rolls the stalks are fed to the group B, which comprise a plurality of tapered rolls 21, see Fig. 4, mounted upon shafts 22 in turn mounted in bearings 23 upon the frame 1. The rolls 21 are pro- 105

vided with ribs 24 which extend longitudinally thereof for their entire length, and fast to each of the shafts 22 is a gear 25. The tapered rolls 21 are grouped in pairs, the 5 rolls of each pair tapering in the same direction with respect to each other, and alternate pairs of rolls taper in opposite directions respectively. The feed space, furthermore, between each pair of rolls 21 is inclined in the opposite direction to the feed 10 space between the pairs of rolls adjacent thereto. By tapering the rolls 21 and arranging said rolls so that alternate pairs of said rolls taper in opposite directions, 15 the path of the stalks between the rolls is changed as it passes from one pair of rolls to the next pair as illustrated in Fig. 12, and this biasing action, in addition to the action of the ribs 24 in bending the stalks, 20 causes the latter to bend and break the woody boon which constitutes the greater portion of the stalk.

From the last pair of rolls 21 the stalks are delivered to the group C which 25 comprises a plurality of tapered rolls 26, see Fig. 5, each of which is mounted upon a shaft 27 in turn mounted in bearings 28 upon the frame 1. Ribs 29 extend longitudinally of the rolls 26 for their entire 30 length and gears 30 fast to said shafts are provided for the purpose of coupling the co-operating pairs of rolls together. The rolls 26 are somewhat smaller in diameter than the rolls 21 and the ribs 29 of the rolls 35 26 are higher than the ribs 24. The rolls 26 are grouped in pairs and the rolls of each pair taper in the same direction with respect to each other and alternate pairs of said rolls taper in opposite directions respectively.

From the rolls 26 the stalks of material are fed to the group D, which consists of a 40 plurality of rolls 31, see Fig. 6, each mounted upon a shaft 32 in turn mounted in bearings 33. The rolls 31 are somewhat smaller in diameter than the rolls 26 and are provided with ribs 34 which extend longitudinally 45 thereof. Gears 35 are provided for each of the shafts 32. Each co-operating pair of rolls 31 is positioned in the same manner as are the rolls 21 and 26.

From the rolls 31 the material is fed to the group E, which consists of a plurality of tapered rolls 36, see Fig. 7, formed integral 55 with shafts 37 mounted in bearings 38 upon the frame 1. The rolls 36 are provided with longitudinal ribs 39 and the co-operating rolls of each pair of rolls are geared together by gears 40. The rolls 36 are somewhat smaller in diameter than the rolls 41, but the action thereof upon the material is 60 practically the same as is the action of all the previously mentioned tapered rolls.

From the rolls 36 the material fed beneath 65 a cross bar 41, see Fig. 8, in which are a

plurality of pins 42 which act to comb and separate the broken particles of boon from the fibers. The material finally passes between a pair of rolls 43, see Fig. 9. The rolls 43 are cylindrical and are mounted 70 upon shafts 44 in turn mounted in bearings 45 upon the frame 1. The rolls 43 are connected together by gears 46.

The various rolls are all rotated in unison and in the proper direction from the main driving shaft 2 and auxiliary driving shafts 14, 15 and 16, to each of which sprockets 47 and 48 are rigidly fastened, the sprockets 47 being located at one end of the shafts and the sprockets 48 at the other end thereof. Alternate pairs of rolls are driven 75 from opposite sides of the machine and sprockets 49 are fastened to one of the shafts for each co-operating pair of rolls, and the latter are driven by a chain 50 which operatively connects a sprocket 47 with a plurality of the sprockets 49, certain of the latter being fastened to an upper roll and other sprockets 49 being fastened to a lower roll. In like manner, upon the other side of the 80 machine sprockets 51 are fastened to certain of the shafts and chains 52 operatively connect the sprockets 48 with the sprockets 51 and the latter are so arranged that the rolls are driven in the proper direction 85 to feed the material therebetween. It is evident that there may be any number of auxiliary driving shafts provided and a greater or lesser number of rolls may be driven from any one driving shaft, if it is 90 so desired.

The material is fed to the cylindrical rolls 17 by a delivery belt 53, and fed away from the rolls 43 by a discharge belt 54. A conveyor belt 55 is positioned beneath the entire row of fiber separating rolls, said belt passing over pulleys 56, one of which is driven by a cross belt 57 from the driving shaft 2 and said conveyor belt is utilized 105 in collecting the broken particles of material which fall from the rolls as the material passes therebetween.

The general operation of the machine hereinbefore specifically described is as follows:—The stalks of material are fed longitudinally thereof to the rolls 17 by the delivery belt 53 and in passing between the cylindrical rolls 17 said stalks are crushed and partly broken. The material then passes successively between the tapered rolls 120 of the groups B, C, D and E, which act upon the stalks in the manner hereinbefore mentioned to open the stalks and break up the woody boon and separate the latter from the fibers until the latter, to which 125 some of the boon is still clinging, are delivered from the machine at the rolls 43 and deposited upon the belt 54. In passing between the tapered rolls, the material is given an added bias, tending to open the 130

stalks, a result which has heretofore never been obtained by using untapered fluted rolls.

I claim:

5. 1. In a machine for separating fibers from the stalks of fiber yielding plants a plurality of rolls grouped in pairs, each pair of rolls being provided with a feed space therebetween, the feed space between one pair of 10 rolls being inclined in the opposite direction to the feed space between the pair of rolls adjacent thereto, and means to rotate said rolls.

15. 2. In a machine for separating fibers from the stalks of fiber yielding plants a plurality of tapered rolls grouped in pairs, the rolls of each pair tapering in the same direction with respect to each other, and alternate pairs of rolls tapering in opposite directions 20 respectively, and means to rotate said rolls.

25. 3. In a machine for separating fibers from the stalks of fiber yielding plants a plurality of tapered fluted rolls grouped in pairs, the rolls of each pair tapering in the same direction with respect to each other, and alternate pairs of rolls tapering in opposite directions 30 respectively, and means to rotate said rolls.

35. 4. In a machine for separating fibers from the stalks of fiber yielding plants a plurality of co-operating cylindrical rolls for crushing and breaking said stalks, a plurality of tapered rolls for bending the stalks, said last-named rolls being grouped in pairs and the rolls of each pair tapering in the same direction with respect to each other and alternate pairs of rolls tapering in opposite directions 40 respectively, and means to rotate said rolls.

45. 5. In a machine for separating fibers from the stalks of fiber yielding plants a plurality of co-operating cylindrical rolls for crushing and breaking said stalks, a plurality of tapered fluted rolls for bending the stalks, said last-named rolls being grouped in pairs, and the rolls of each pair tapering in the same direction with respect to each other

and alternate pairs of rolls tapering in opposite directions respectively, and means to rotate said rolls.

6. A machine for separating fibers from the stalks of fiber yielding plants having, 50 in combination, a frame, a plurality of tapered rolls grouped in pairs upon said frame, the rolls of each pair tapering in the same direction with respect to each other and alternate pairs of rolls tapering in opposite 55 directions respectively, and means to rotate alternate pairs of rolls from opposite sides of the frame.

7. In a machine for separating fibers from the stalks of fiber yielding plants a plurality 60 of co-operating cylindrical rolls for crushing and breaking said stalks, a plurality of tapered fluted rolls for bending the stalks, said last-named rolls being grouped in pairs and the rolls of each pair tapering in the 65 same direction with respect to each other and alternate pairs of rolls tapering in opposite directions respectively, said tapered rolls also decreasing in diameter from the inlet toward the discharge end of the machine, and means to rotate said rolls.

8. In a machine for separating fibers from the stalks of fiber yielding plants a plurality of co-operating cylindrical rolls for crushing and breaking said stalks, a plurality of tapered fluted rolls for bending the stalks, said last named rolls being grouped in pairs and the rolls of each pair tapering in the same direction with respect to each other and alternate pairs of rolls tapering in 75 opposite directions respectively, said tapered rolls also decreasing in diameter and the 80 grooves and ridges thereon decreasing in size from the inlet toward the discharge end of the machine, and means to rotate said 85 rolls.

In testimony whereof I have hereunto set my hand.

THOMAS G. BOOTH.
